UNITED STATES PATENT OFFICE.

RUFUS T. RAY AND BAKER B. RAY, OF FOSTORIA, OHIO.

AUTOMATIC STAMP-VENDING MACHINE.

1,128,721.

Specification of Letters Patent. Patented Feb. 16, 1915.

Application filed December 22, 1913. Serial No. 808,221.

To all whom it may concern:

Be it known that we, RUFUS T. RAY and BAKER B. RAY, citizens of the United States, residing at Fostoria, in the county of Seneca and State of Ohio, have invented certain new and useful Improvements in Automatic Stamp-Vending Machines, of which the following is a specification.

The present invention relates to certain 10 new and useful improvements in coin actuated stamp vending machines, and has for its object to provide a device of this character which embodies mechanical means for feeding a continuous strip of stamps and 15 severing the individual stamps in the proper manner preparatory to discharging the same from the machine.

Further objects of the invention are to 20 provide a stamp vending machine which is comparatively simple and inexpensive in its construction, which is positive and reliable in its operation, which is not liable to get 25 out of repair, and which can be readily modified to handle stamps of any denomination.

With these and other objects in view, the invention consists in certain novel combinations and arrangements of the parts as will 30 more fully appear as the description proceeds, the novel features thereof being pointed out in the appended claims.

For a full understanding of the invention, reference is to be had to the following description and accompanying drawings, in 35 which:—

Figure 1 is a perspective view of a stamp vending machine constructed in accordance with the invention. Fig. 2 is an enlarged longitudinal sectional view through one side 40 of the machine, showing the mechanism for handling one cent stamps. Fig. 3 is a transverse sectional view on the line 3—3 of Fig. 2. Fig. 4 is an enlarged side elevation of the cam mechanism for operating the feed rolls. Fig. 5 is a plan view of the same, and Fig. 6 is a detail view of the detent mechanism employed for vending two cent stamps.

Corresponding and like parts are referred to in the following description and indicated 50 in all the views of the drawings by the same reference characters.

Specifically describing the present embodiment of the invention, the numeral 1 designates the outer casing within which the

stamp vending mechanism is mounted. 55 This casing is shown as subdivided by the partition 2 into separate compartments, the one cent stamp vending mechanism A being mounted within one of the compartments, while the two cent stamp vending mechanism B is mounted within the opposite compartment. These two stamp vending mechanisms A and B are substantially alike, so that with the explanation of the detail construction of the coin actuated trip mechanism, a description of one will suffice for both.

Each of the stamp vending mechanisms A and B includes a main drive wheel 3 mounted upon a shaft 4. A spiral spring 5 is applied to the shaft and drive wheel 3 for the purpose of turning the same. This spring 5 is designed to be wound by means of a key or the like in the usual manner, the customary pawl and ratchet 6 being provided 75 for maintaining the spring under tension until the tension is relieved by rotation of the wheel 3. Doors 7 are shown as provided in the ends of the main casing 1 to admit of access being had to the interior thereof for 80 the purpose of winding the springs 5.

The drive wheel 3 has a toothed periphery and meshes with an operating gear 8 upon shaft 9, the said gear 8 in turn meshing with a pinion 10 upon a shaft 11. This 85 shaft 11 is shown as provided with a retarding fan 12 which acts as a governor to prevent a too rapid turning of the wheels when the mechanism is released. Rigid with the operating gear 8 are the disks 13 and 14, 90 the former being provided with a cam projection 15, while the latter is formed with a peripheral notch 16. A roller 17 at the end of a coin actuated detent 18 is normally seated within the notch 16 so as to lock the 95 operating gear 8 against turning. A spring 19 serves to hold the coin actuated detent 18 in operative position, the said detent being arranged at the lower end of a coin chute 20 which extends upwardly and forwardly 100 at the top thereof.

The stamps to be vended are formed in continuous strips and purchased in rolls. A roll 21 of stamps is suitably supported at the rear of the casing, the free end 22 of 105 the strip of stamps being drawn over an idler 23 and carried between a pair of feed rolls 24 and 25. That one of the feed rolls

which comes into contact with the cam surface of the stamps is preferably formed with a wax surface so as to eliminate any possibility of the stamps adhering or sticking thereto. As the stamps emerge from the two feed rolls 24 and 25 they pass through a guide chute 26 which prevents the extremity of the stamp strip from curling. A fixed knife edge 27 is arranged at the outer end of the guide chute 26, being properly positioned for coöperation with a knife edge 28 at the lower end of a vertically reciprocating plunger 29. A suitable guide 30 may be provided for this plunger 29, the upper end of which is pivotally connected to one end of a lever 31, which is pivotally mounted at an intermediate point in its length at 32. The opposite end of the lever is connected to a second plunger 33 having a roller 34 at its lower end which normally travels upon the before mentioned disk 13. A spring 35 engages the rear end of the lever 31 so as to normally hold the roller 34 yieldably against the periphery of the disk 13 and hold the knife edge 28 in an elevated position. However, when the cam projection 15 of the disk 13 is brought into engagement with the roller 34 so as to force the plunger 33 upwardly, the opposite plunger 29 is moved downwardly so as to bring the knife edge 28 into engagement with the knife edge 27 and sever that portion of the extremity of the stamp strip 22 which is projected beyond the guide chute 26.

As a means for supporting the stamp roll 21, a pair of arms 37 are shown as pendent from the top of the casing 1, the said arms having suitable pivot points 38 for engaging a wooden core 39 or the like upon which the stamps may be wound. These arms 37 may have a spring formation, and are shown as provided at their lower ends with forwardly projecting extensions 40 between the extremities of which the guide roller or idler 23 is journaled. Suitable doors 41 may be provided in the rear of the casing 1 for placing new stamp rolls 21 in position when the former stamp roll has been exhausted.

50 Loose upon the shaft 42 of the lower feed roll 25 is a pinion 43 which meshes with a rack 44 upon a reciprocating rack bar 45. This pinion 43 carries a pawl 46 which is normally held in a spring engagement with a ratchet wheel 47 keyed upon or otherwise made rigid with the shaft 42. A spring 48 connects the forward end of the reciprocating rack 45 to the front of the casing 1, while the rear end of the reciprocating rack bar 45 is provided with a finger 49 adapted to be engaged by a cam 50 rigid with the main operating gear wheel 8. Upon the backward or rearward movement of the reciprocating rack bar 45 the spring pawl 46 engages the ratchet wheel 47 so as to rotate the shaft 42 and feed wheel 25 and thereby unroll the stamp strip, the extremity thereof being caused to project beyond the end of the guide chute 26 a sufficient amount so that one stamp will be severed therefrom 70 upon the operation of the cutting mechanism. Upon the forward or return movement of the reciprocating rack bar 45, caused by the spring 48, the spring pawl 46 will slip over the teeth of the ratchet wheel 47, so that there will be no backward or reverse turning of the feed wheels.

55 As previously explained, the spring 5 of the main drive wheel 3 is always under tension, although rotation of the operating wheel 8 is prevented by engagement of the roller 17 of the coin actuated detent 18 with the notch 16. When a one cent coin 51 is dropped in the coin chute 20, it falls to the lower end thereof and rests upon the detent 18, the space between the detent and the discharge end of the chute being normally less than the diameter of the coin so that the coin is held in position between the inclined rear edge of the coin chute and the head 52 at the rear end of the operating plunger 53. This plunger is normally held in a retracted position by the spring 54, the free end of the plunger projecting beyond the front of the casing 1 so as to be readily manipulated by the operator. After the coin has been dropped into the coin chute 20 and permitted to come to rest upon the detent 18, as indicated in Fig. 2, the operator presses inwardly upon the plunger 53, thereby forcing the coin 51 rearwardly and wedging the same between the inclined rear edge of the coin chute and the detent 18, thereby forcing the detent 18 downwardly against the action of the spring 19. The roller 17 is thus moved out of the notch 16 so as to release the main operating gear wheel 8. The coin 51 may then drop upon the bottom of the casing 1, although the roller 17 will ride upon the periphery of the disk 14 until the operating gear wheel 8 has completed one revolution, when it will again drop into the notch 16 and stop the mechanism. This complete revolution of the main operating gear 8 serves, however, to 115 reciprocate the rack bar 45 so as to unroll the stamp strip 22 a sufficient amount to cause one stamp to project beyond the end of the guide chute 26, and also to bring the cam projection 15 of the disk 13 into engagement with the roller 34 so as to lift the plunger 33 and operate the cutting mechanism. The stamp which is thus severed from the strip may be dropped upon the curved guide 55 and then be discharged through a suitable opening 56 in the front of the casing. It will thus be obvious that the plunger 53 can be freely operated at any time from the front of the main casing 1, although the stamp feeding and cutting 125 130

mechanism is only set in operation when a coin has been previously dropped into the coin chute 20 and permitted to come to rest upon the detent 18 in front of the head 5 52 of the plunger 53.

The two cent stamp vending mechanism B (see Fig. 6) is identical in construction with the one cent stamp vending mechanism A, with the exception that the notched detent engaging disk 14^a which corresponds to the disk 14 of the one cent stamp vending mechanism is provided with two peripheral notches 16^a instead of a single notch 16. These two peripheral notches 16^a are 10 arranged at diametrically opposite points so that when the operating gear wheel 8 is initially released by dropping the first penny in the coin chute 20 and pressing inwardly upon the plunger 53, it only turns a 15 half revolution instead of a complete revolution, the roller 17 of the detent 18 dropping into the opposite notch 16^a. In order to complete the revolution of the gear wheel 8 which is necessary to obtain the stamp, 20 a second penny must be dropped into the coin chute 20 and the plunger 53 operated a second time. The gear wheel 8 then revolves through a second half revolution, thereby completing the entire revolution 25 which is necessary, as in the previous instance, to unroll the proper length of the stamp strip and actuate the cutting mechanism to sever the projecting stamp. As 30 illustrated, the one cent stamp mechanism 35 is shown as mounted in one end of the casing 1, and the two cent stamp mechanism mounted in the opposite end of the casing, although it will be obvious that there are many other possible arrangements and that 40 by slight modifications the mechanism can be readily adapted for the vending of stamps of all denominations.

Having thus described the invention, what we claim as new and desire to secure by Letters Patent, is:—

1. A stamp vending machine including feed rolls, means for supplying a continuous stamp strip to the feed rolls, driving means having an operative connection with the feed rolls, means controlling the driving means, a guide chute receiving the end of the stamp strip from the feed rolls, a fixed knife edge at the end of the guide chute, a lever pivoted between its ends, a 50 plunger connected to one end of the lever and provided with a reciprocating knife mounted for coöperation with the fixed knife edge, a second plunger connected to the opposite end of the lever, and cam 55 means driven by the driving means for actuating the second plunger.

2. A stamp vending machine including feed rolls, means for supplying a continuous stamp strip to the feed rolls, a loosely 60 mounted pinion having a pawl and ratchet

connection with one of the feed rolls, a reciprocating rack bar engaging the pinion, driving means, cam means actuated by the reciprocating rack bar, and cutting means for severing the extremity of the stamp 70 strip.

3. A stamp vending machine including feed rolls, means for supplying a continuous stamp strip to the feed rolls, an operating wheel, a spring actuated drive wheel 75 normally tending to rotate the operating wheel, a pair of cams rigid with the operating wheel, means actuated by one of the cams for operating the feed rolls, cutting means actuated by the opposite cam for severing the end of the stamp strip, a notched disk rigid with the operating wheel, and detent means coöperating with the notched disk to control the operation of the machine. 85

4. A stamp vending machine including feed rolls, means for supplying a continuous stamp strip to the feed rolls, an operating gear wheel, a spring actuated drive wheel meshing with the operating gear 90 wheel, a pair of cams rigid with the operating wheel, a pinion having a pawl and ratchet connection with one of the feed rolls, a reciprocating rack bar engaging the pinion and actuated by one of the cams, a reciprocating plunger actuated by the other 95 cam, cutting means including a movable knife, a plunger carrying the movable knife, an operative connection between the said plunger and the cam actuated plunger, and 100 means for controlling the operating wheel.

5. A stamp vending machine including feed rolls, means for supplying a continuous stamp strip to the feed rolls, a guide chute receiving the end of the stamp strip 105 from the feed rolls, a fixed knife edge at the end of the guide chute, a reciprocating plunger provided with a movable knife edge mounted for coöperation with the fixed knife edge, an operating gear, a spring actuated drive gear meshing with the operating gear, a pair of cams rigid with the operating gear, a pinion having a pawl and ratchet connection with one of the feed 110 rolls, a reciprocating rack bar engaging the pinion and actuated by one of the cams, a plunger actuated by the opposite cam, an operative connection between the said plunger and the knife edge carrying plunger, a notched disk rigid with the operating 115 gear, and detent means coöperating with the notched disk to control the operation of the machine. 120

6. A stamp vending machine including feed rolls, means for supplying a continuous stamp strip to the feed rolls, a guide chute receiving the end of the stamp strip from the feed rolls, a fixed knife edge at the end of the guide chute, a reciprocating plunger provided with a movable knife 125 130

mounted for coöperation with the fixed knife edge, an operating gear, a pair of cams rigid with the operating gear, a pinion having a pawl and ratchet connection 5 with one of the feed rolls, a reciprocating rack bar engaging the pinion and actuated by one of the cams, a plunger actuated by the opposite cam, an operative connection between the said plunger and the knife car-

rying plunger, and means for controlling 10 the operating gear.

In testimony whereof we affix our signatures in presence of two witnesses.
